UNITED STATES PATENT OFFICE.

DAVID S. JACOBUS, OF JERSEY CITY, NEW JERSEY, AND JOHN WOLFF, OF EAST CLEVELAND, OHIO, ASSIGNORS TO THE BABCOCK & WILCOX COMPANY, OF BAYONNE, NEW JERSEY, A CORPORATION OF NEW JERSEY.

STEAM BOILER.

Application filed January 20, 1920. Serial No. 352,678.

To all whom it may concern:

Be it known that we, DAVID S. JACOBUS and JOHN WOLFF, citizens of the United States, and residing at Jersey City, county 5 of Hudson, and State of New Jersey, and East Cleveland, in the county of Cuyahoga and State of Ohio, respectively, have invented certain new and useful Improvements in Steam Boilers, of which the following is a 10 specification.

Our invention more particularly relates to an improvement in a boiler in which a boiler part or parts, such as a mud drum and the metallic supporting members therefor, which 15 are to be protected from the furnace heat, are located above the stoker, and in which an ignition arch is located between the stoker and the parts to be protected and affords protection to such parts. In practice, the inner end of such an arch is liable to fail, and in case of failure the boiler parts 20 are exposed to the furnace heat and injured unless the stoker is promptly shut down.

In accordance with our present invention, 25 a bridge wall is located immediately above the arch and in front of the parts to be protected and is supported independently of the ignition arch so that a failure of the ignition arch does not affect the protection afforded to said parts.

Other objects of our invention will appear in the specification and will be particularly pointed out in the claims.

Referring, now, to the drawings, Figure 35 1 is a longitudinal sectional view of a steam boiler of the Stirling type, in conjunction with which we have illustrated our invention, and Fig. 2 is a detail sectional view similar to Fig. 1, but illustrating the parts 40 with which our present invention is concerned on a larger scale.

Referring, now, to the drawings, in which like reference characters indicate like parts, 10, 11 and 12 are the upper steam and water 45 drums of a steam boiler of the Stirling type, in conjunction with which we have illustrated our invention, connected to a lower mud drum 13 by banks of tubes 14, 15 and 16, respectively. The gases from the furnace 50 are directed serially over the tubes by baffles 17, 18, 19 and 20, the baffle 17 extending upwardly from the mud drum 13 back of the front row of the first bank of tubes, the baffle 18 extending downwardly from the

steam and water drum 11 back of the front 55 row of tubes of the second bank 18, the baffle 19 extending upwardly from the mud drum immediately back of the second bank of tubes 15, and the baffle 20 extending downwardly from the steam and water drum 20 60 between the tubes of the last bank 16, the baffle 19 preferably being provided with a transverse projection 19^a which directs the gases among the front rows of tubes of the last bank as they pass downwardly. The 65 gases pass in the general direction indicated by the arrows, and escape through the outlet 21. The setting for the boiler is indicated at 22. Beneath the mud drum 13 is disposed a stoker 23, which is here shown as of 70 the chain grate type. Above the stoker and beneath the mud drum is disposed an ignition arch 24 which is supported from metallic members 25, here shown as channel irons, in a known manner, it being understood that "ignition arch" is a broad expression, covering any refractory roof above the furnace, either suspended or otherwise supported, or flat or of other form. Above the inner end of the ignition arch 24 is disposed a bridge wall, 80 which is indicated, in general, by the reference character 26, and which comes in front of the mud drum 13. This bridge wall is supported by metallic members, such as I-beams 27, extending transversely across the 85 furnace, and comprises an arch 28, which is located immediately above the ignition arch 24, and which is suspended from the metallic members 27 in any of the well known ways, such as by hooks engaging the 90 flanges of the I-beams 27. The bridge wall also comprises a wall proper 29 carried on the I-beams 27, a section 30, which may be formed of tiles, being disposed between the arch 28 and the wall member 29, and resting on the arch 28. A dust floor 31 is preferably located at the rear of the bridge wall and forms a gas-tight joint therewith and with the setting 22. The dust floor 31 partially encloses a portion B of the passage 95 which conducts the gases from the furnace. No casing is built up at the front of the space A between the ignition arch and the dust floor 31, so that this space is freely exposed to the atmosphere. By leaving the 100 space A free to the atmosphere there is no tendency to draw the hot gases from the furnace through cracks in the ignition arch or

105

through any openings around the brickwork which comes above the inner end of the ignition arch. If the casing extended completely over the front of the opening A so as to encase the space A, any leakage through the roof of the space A would tend to create a draft suction within the space A higher than that within the furnace, with the result that there would be leakage from the furnace through the roof 24, as well as through the brickwork which comes above the inner end of the ignition arch. The suction within the space B is considerably greater than that within the furnace and it 15 will readily be seen that any leakage through the partition between the spaces B and A would tend to increase the draft suction in the space A, should the space A be encased, to a point where the draft suction of A 20 would be higher than the draft suction within the furnace. For example, the draft suction at B might be $1\frac{1}{2}$ ". With no casing to enclose the space A, the draft suction in A 25 would remain zero. Should a casing be added, the draft suction in A might be as high as 1", whereas, the draft in the furnace might be, say .6", and the result would be a tendency for the hot gases to be drawn outward through the brickwork and into the 30 space A. Where there is a tendency to draw the hot gases outward and the gases percolate slowly through the brickwork, it is much harder to maintain the brickwork than where the cold air percolates slowly through 35 the brickwork and into the furnace. In fact, in many instances, the percolation of the hot gases outward as compared with the percolation of the cold air inward makes all the difference between a failure and a success of the installation.

While we have herein shown and described one modification of our invention, we do not desire to be limited to the exact arrangement shown and described, but seek 45 to cover, in the appended claims, all those modifications which come within the true spirit and scope of our invention.

What we claim and desire to secure by Letters Patent of the United States is:

50 1. In a furnace for a steam boiler, an ignition arch, supporting members independent of said arch, a bridge wall located in front of a boiler member to be protected and above said ignition arch and supported by said supporting members, said bridge wall comprising an arch suspended from said supporting members.

55 2. In a furnace for a steam boiler, an ignition arch, a bridge wall located in front of a boiler member to be protected and above said ignition arch, supporting members independent of said arch disposed thereabove and extending transversely thereof, an arch extending transversely 60 of the ignition arch and suspended from

said supporting members, and a wall carried by said supporting members and disposed in front of the member to be protected.

3. In a furnace for a steam boiler of the water tube type comprising a mud drum, an ignition arch, a bridge wall located above said arch and in front of the mud drum of the boiler, said wall comprising supporting members independent of said arch, a wall carried by said supporting members, an arch suspended beneath said supporting members, and a filling member of refractory material disposed between the suspended arch and the supported wall.

4. In a furnace for a steam boiler comprising a plurality of upper steam and water drums connected by banks of tubes to a lower mud drum, a stoker located beneath the mud drum of the boiler, an ignition arch located above said stoker, and a bridge wall supported independently of said ignition arch and located immediately above said arch and in front of the mud drum of the boiler.

5. In a furnace for a steam boiler, an ignition arch, a bridge wall supported independently of said arch and located above the same and in front of a boiler member to be protected, and a dust floor located behind said wall and forming a substantially gas-tight joint therewith.

6. In a furnace for a steam boiler having upper steam and water drums and a lower mud drum and having a bank of tubes connecting the rear steam and water drum with the mud drum, an ignition arch, supporting members independent of said arch, and a protecting structure for the mud drum positioned above said ignition arch and located with respect to said furnace in front of the mud drum of the boiler, said protecting structure comprising an arch suspended from said supporting members and a wall supported on said supporting members.

7. In a furnace for a steam boiler having upper steam and water drums and a lower mud drum and having a bank of tubes connecting the rear steam and water drum with the mud drum, an ignition arch, supporting members independent of said arch, and a protecting structure for the mud drum positioned above said ignition arch and located with respect to said furnace in front of the mud drum of the boiler, said protecting structure comprising an arch suspended from said supporting members and a wall supported on said supporting members, the combustion space of the furnace opening into a free open space located between the rear furnace wall and the bank of tubes connecting the rear steam and water drum and the mud drum.

8. In a furnace for a steam boiler having upper steam and water drums and a lower

mud drum and having a bank of tubes connecting the rear steam and water drum with the mud drum, an ignition arch, supporting members independent of said arch, a protecting structure for the mud drum positioned above said ignition arch and located with respect to said furnace in front of the mud drum of the boiler, said protecting structure comprising an arch suspended from said supporting members and a wall supported on said supporting members, and a stoker located beneath the mud drum of the boiler, the combustion space of the furnace opening into a free space located between the rear furnace wall and the bank ¹⁵ of tubes connecting the rear steam and water drum and the mud drum.

DAVID S. JACOBUS.
JOHN WOLFF.
